The ornamental design for a modular utility rack, as shown and described.

DESCRIPTION

FIG. 1 is a perspective view of a modular utility rack showing our new design;

FIG. 2 is a front plan view thereof;

FIG. 3 is a left plan view thereof;

FIG. 4 is a right plan view thereof;

FIG. 5 is a top plan view thereof;

FIG. 6 is a bottom plan view thereof; and,

FIG. 7 is a rear plan view thereof.

The broken lines showing are for the purposes of illustrating the environment of the article only and form no part of the claimed design.

The wavy broken lines represent that no particular length is claimed.
